UNITED STATES PATENT OFFICE.

HENRY SCHWARBER, OF HOBOKEN, NEW JERSEY, ASSIGNOR TO INFLEXIBLE COMPANY, OF WEST NEW YORK, NEW JERSEY.

DESIGN FOR LACE.

43,258.

Specification for Design.

Patented Nov. 19, 1912.

Application filed August 31, 1912. Serial No. 718,146. Term of patent 3½ years.

To all whom it may concern:

Be it known that I, HENRY SCHWARBER, a citizen of the Republic of Switzerland, residing at Hoboken, in the county of Hudson and State of New Jersey, have invented a new, original, and ornamental Design for Laces, of which the following is a specification, reference being had to the accompanying drawing, forming part thereof.

The figure is a plan view of a portion of lace showing my design.

I claim—

The ornamental design for lace, as shown.

HENRY SCHWARBER.

Witnesses:

CHAS. B. UHLER,
CONRAD KELLER.
